UNITED STATES PATENT OFFICE.

JOSHUA POOL AND JOSEPH POOL, OF GREENSBURG, INDIANA.

DESIGN FOR MONUMENTS.

SPECIFICATION forming part of Design No. 11,792, dated May 25, 1880.

Application filed May 3, 1880. Term of patent 7 years.

To all whom it may concern:

Be it known that we, JOSHUA POOL and JOSEPH POOL, both citizens of the United States, residing at Greensburg, in the county 5 of Decatur and State of Indiana, have invented and produced a new and original Design for a Monument, of which the following is a specification, reference being had to the accompanying drawing, forming part thereof, 10 in which our newly-designed monument is fully illustrated by a single side elevation.

The leading feature of our new design consists of the monument hereinafter described, which is mounted on a square base, A, made of 15 two or more pieces.

The first section of the monument above the base A is the base B, which is square, having its top finished with four gables, B', formed of straight lines, with slanting roofs, and a square 20 center, B², which tapers from the outer surface of the base B to the base of the die C, and forming a fit with said die.

The die C is square, and rests on the base B. On each side of the die C is a panel, C', with 25 gables. Said panels may be sunk below or raised above the surface of the die C.

The cap D is square, and the lower part 30 molded, as shown. The upper part of the cap D is finished with four gables, D', one on each side, formed of straight lines, with slanting roofs or tops, and a square center, D², which tapers from the outer edges of the square part D to its union with its square part D³, at a point about midway of the height of said cap 35 D, the part D³ having vertical sides which extend up to near its top perfectly square, and its top beveled to fit the base of the spire E.

The spire E is square and has projecting 40 gables E' at its base on each of the four sides, as shown.

What we claim as new, and desire to secure by Letters Patent, is—

1. The design of a sectional monument to be mounted on the square base A, consisting of a square base, B, with slanting-topped gables B' on its four sides, and a square center, B², tapering from the outer edges of the base to the die C, the square die C, having sunk or raised panels C', with gables on all four of its sides, the cap D, having molding on its lower part and slanting-topped gables D' at the top, one on each side, and a square tapering center, D², with the square part D³, having vertical walls, and running straight to near the top, and beveled at the top to fit the base of the 50 square spire E, and the square spire E, finished with projecting gables E' on its four sides at the base, as shown and described. 55

2. The design of a monument with its various sections fitted together, consisting of the base 60 B, the die C, the cap D, and the spire E, each being provided with slanting-topped gables, except the die C, and slanting-topped panels raised or sunk on all four sides, the base B and cap D, having square centers tapering from the outer edges of said base and cap to fit the sections above each of them, substantially as shown and described. 65

3. The design as a whole, and each section separately, except the base B, and each part 70 of each section, as shown and described.

In testimony whereof we have signed our names to this specification in the presence of two subscribing witnesses.

JOSHUA POOL.
JOSEPH POOL.
